CLAIM

The ornamental design for a unit for securing bed sheets which is to be placed between mattress and boxspring, as shown and described.

DESCRIPTION

FIG. 1 is a front elevational view of a unit for securing bed sheets which is to be placed between mattress and boxspring showing our new design;

FIG. 2 is a rear elevational view thereof;

FIG. 3 is a side view, taken from the left side of FIG. 1, the right side view being a mirror image thereof; and, FIG. 4 is a top plan view thereof; the bottom plan view being a mirror image thereof.

The broken line squares, with diagonal crosses in them, on the claimed design in the FIGS. 1 and 2 views represent stitching.

The broken lines showing a mattress in FIG. 1 are for illustrative purposes only and form no part of our claimed design.
